Filed Nov. 21, 1960, Ser. No. 63,077

Term of patent 14 years

(Cl. D62—3)

FIG. 1.

FIG. 2.

FIG. 3.

FIG. 4.

FIGURE 1 is a side elevational view of a ventilator cover, showing my new design.

FIGURE 2 is an end elevational view, thereof.

FIGURE 3 is a top plan view.

FIGURE 4 is a side elevational view of a modified form of the ventilator cover shown in FIGURES 1, 2 and 3.

The end and side of the ventilator cover not disclosed are the same as the end and side shown in FIGURES 1 and 2, respectively. The bottom is open, the ventilator cover being hollow.

I claim:

The ornamental design for a ventilator cover or similar article, substantially as shown and described.
